UNITED STATES PATENT OFFICE

WALTER A. TROTH, OF BROOKLYN, NEW YORK

HOUSEHOLD-WASTE BALER

Application filed November 21, 1928. Serial No. 320,938.

This invention relates to balers and the improvements are directed to a novel form of structure adapted to receive waste paper, or the like, for subsequent baling to a compact 5 size for easy handling.

Heretofore it has been the universal practice to deposit and accumulate newspapers, or similar material, in ordinary waste paper baskets in the home and when filled to capacity the same are emptied into larger containers, such as barrels in a backyard for collection by certain city departments. It is obvious that the accumulation of the waste pieces of paper in loose form tends to produce 15 a scattering of the same during a windstorm, or the like, and hence an untidy condition is bound to exist.

Accordingly, it is the primary object of the present invention to produce a baler 20 wherein waste paper may be deposited as desired and finally reduce to package form to facilitate portage without loss of the contents.

Another object is to provide means in the 25 form of an interlocking top frame member adapted to cooperate with the side walls of the baler to maintain the covering material for the waste paper in position during the depositing of the waste paper in the baler, said 30 means being removably carried by said side walls to permit of displacement to complete the packaging of the paper.

Still another object of the invention resides in the provision of means to permit the 35 application of a tying member, such as a string or the like, to the baler, said member or members being maintained in position during the filling of the baler and ready to be applied over the package after the former is 40 filled.

A still further object is to provide a baler of the above-mentioned character, which comprises but a few simple parts, preferably 45 of knock-down construction, and which is neat and attractive in appearance in addition to the features set forth hereinbefore.

With these objects in view, together with others which will appear as the description 50 proceeds, the invention resides in the novel formation, combination, and arrangement of

parts, all as will be described more fully hereinafter, illustrated in the drawings, and particularly pointed out in the claims.

In said drawings:

Figure 1 is a plan view of the baler with 55 parts broken away to expose certain clip elements.

Fig. 2 is a vertical, longitudinal sectional view taken on the line 2—2 of Fig. 1.

Fig. 3 is a transverse section taken on the 60 line 3—3 of Fig. 2.

Fig. 4 is a central, longitudinal vertical sectional view taken at right angles to that shown in Fig. 2, and illustrating the placement of the tying elements and the enveloping cover 65 in the baler.

Fig. 5 is a perspective view of the waste paper reduced to package form, said view being somewhat reduced in size.

Referring now in detail to the accompanying 70 drawings, wherein like characters of reference denote similar parts throughout the several views, let 10 represent generally my improved baler, the same in assembled condition producing a container having an open 75 top portion to facilitate the depositing of waste material therein and including a false bottom 11 preferably positioned above the base of the baler.

The details of construction will be readily 80 understood upon inspection of the drawings, with special reference to Figs. 2 and 4, wherein it will be observed that I have provided a base member 12 in the form of a frame and having a continuous groove 13 extending 85 downwardly from the top face thereof. The top member 14 is somewhat similar in construction to said base member 12, in that it is a frame-like structure having a continuous groove 15 extending upwardly from the bottom face thereof, both of said grooves being adapted to receive the extremities of the pieces 16, 17, 18 and 19, as clearly shown in 90 said drawings, to thus form the four side walls of the baler.

The structure thus far disclosed includes the top and bottom members and the side walls, the resulting structure presenting both ends open, and while the top opened portion 100 affords a convenient means for the deposit

of material, it becomes necessary to provide a bottom upon which the material may rest during its accumulation. To this end it is proposed to mount two side members 20 and 21 against the lower inside surfaces of opposite side walls, the lower ends of said members 20 and 21 resting upon the top face of said base member 12, as clearly shown in Fig. 2. With these members 20 and 21 so located it is only necessary to place a plurality of pieces of wood upon the top edges thereof, said pieces bridging therebetween and forming the bottom of the baler, as shown in Figs. 2 and 4.

In assembling the structure the side walls having their lower ends inserted in said groove 13 in said base member 12, whereupon the upper ends thereof are entered into the groove 15 of said top member 14, thus producing a construction securely maintained in position, yet of knock-down formation. To construct the false bottom 11, said pieces 20 and 21 are laid edgewise upon the face of said base member 12 and the pieces forming said bottom laid thereacross, thus completing the baler.

In view of the fact that waste pieces of paper of varying sizes will be placed in the baler, it is proposed to provide means for enveloping the said waste paper and also means whereby a tying element, in the form of a piece of string, or pieces of string, may be positioned to securely maintain the accumulation of waste in a package form. To this end, the top edges of said side members 16, 17, 18 and 19, are each notched, as indicated at 22, to receive the strings, which extend exteriorly of the baler, as shown in Fig. 4, and abut the sides and bottom of the same. The enveloping means 24, may be formed from wrapping paper, or old newspapers, and comprises two similar pieces, arranged in superimposed relation and at right angles to each other across the bottom 11, rising vertically upward against the respective sides of the baler and extending in pendant relation exteriorly thereof, as clearly shown in Fig. 4. It will, of course be understood that in placing the strings 23 and enveloping means 24, said top member 14 is elevated from the top edges of said side members to permit the engagement of the strings with said notches 22, and since the upper portions of said enveloping means 24 lie over said top edges of said side members, the replacement of said top member firmly anchors that portion of the enveloping means within the groove 15 and accidental displacement thereof is obviously precluded.

From the foregoing it is apparent that the two pieces of newspaper or the like, comprising the enveloping means 24, substantially forms a lining for said baler and as the strings 23 are positioned outside the lining, but interiorly of the baler, both are in posi-

tions to complete the package, and at the same time firmly associated with said baler. During the placement of the enveloping means and prior to the attachment of the top frame member 14, it is convenient to insert the former beneath clip members 25, see Fig. 1, said members permitting an even placement of said enveloping means within the baler, so that the said means may neatly contact the bottom and sides thereof. A supply of string 26 may be positioned beneath the bottom 11, as shown in Fig. 2.

In home use the housewife deposits paper, or other accumulations of waste material, in the baler from time to time, and as the pile increases said material may be pressed downwardly to secure compactness, and finally when the baler is filled and packed, as aforesaid, the top member 14 is removed, the free ends of the pieces of paper forming the enveloping means are turned inwardly and overlappingly across the top of the waste paper and the ends of the string drawn up tight and knotted and thus a bale is formed in and then withdrawn from said baler, said bale assuming the illustration shown in Fig. 5 and thus presenting a convenient form of package for the carrying-away of the waste material.

While the present is a disclosure of the preferred embodiment of the invention it is to be understood that the same is not limited thereto, as various changes in the minor details of construction, proportion and arrangement of parts, may be resorted to without departing from the spirit of the invention as defined in the appended claims.

I claim:

1. A baler comprising a bottom frame member having a groove in its upper face, a top frame member having a groove in its bottom face, side walls having their lower ends removably mounted in the groove in said bottom frame member and having their upper ends removably mounted in the groove in said top frame member, a removable bottom for said baler, and clips carried by the top edges of said side walls for securing an enveloping means within said baler.

2. A baler comprising top and bottom frame members, each being provided with a groove, a plurality of side walls having their ends removably mounted in said grooves, a removable bottom for said baler and means carried by the top edges of said side walls for securing an enveloping means within said baler.

3. A baler comprising a bottom frame member having a groove in its upper face, a top frame member having a groove in its bottom face, side walls having their extremities removably mounted in the grooves of said bottom and top frame members, a removable bottom for said baler, side members having their lower ends supported by said bottom

frame member and adapted to support said removable bottom thereabove, and means carried by the top edges of said side walls for securing an enveloping means within said

5 baler.

In testimony whereof I affix my signature.

WALTER A. TROTH.
